HERVEY G. CRAM, OF BUCKSPORT, MAINE, ASSIGNOR TO MAINE SEABOARD PAPER COMPANY, OF BUCKSPORT, MAINE, A CORPORATION OF MAINE

DIGESTION OF FIBROUS MATERIAL

Application filed December 31, 1932. Serial No. 649,685.

This invention relates to the digestion of fibrous material as practiced, for example, in the preparation of pulp for the manufacture of paper, and the object is to provide a process more efficient and rapid than those hitherto known.

My invention will be well understood from the description of an illustrative embodiment thereof taken in connection with the accompanying drawing, wherein I have shown diagrammatically a digester installation.

For convenience I shall first describe diagrammatically one form of my process as applied to the preparation of paper pulp by the sulfite process, although not limited thereto, and likewise for convenience will use specific quantitative figures in the description which are to be taken, however, as illustrative merely and not as limitations.

Referring to the drawing, the digester 3 there shown may be filled with suitably prepared chips. The cover is fastened securely, valve 5 to the overflow line is opened and acid is pumped from storage tank 7 by means of pump 9 into the bottom of the digester until it is completely filled, as indicated by the flow of acid through the overflow line, at which time the valve 5 is closed. Pumping may now be continued until the pressure capacity of the pump 9 is reached and a high pressure booster pump 11 may then take the burden and be continued in operation until a pressure is reached in the digester preferably markedly in excess of the pressure at which the cooking is to take place, for example, a pressure in the neighborhood of 125 pounds per square inch gage. By this means the acid is forced into the interior of the chips, thoroughly saturating the same, as is indicated by the fact that approximately 20% additional acid is added to the digester by means of this pressure, the excess being absorbed in the interior of the chips. Since the digester is completely filled with liquid and the pressure of the pump is exerted through a column of the liquid in the connecting piping, the chips are completely submerged. There is no opportunity for any to float on the surface of the liquor resulting in incomplete penetration or later causing

burning and discoloration of the pulp product.

We have now provided thoroughly saturated chips in good condition for cooking by treatment under a pressure at least substantially equal to the cooking pressure, which for purposes of illustration might be considered as in the neighborhood of 75 pounds, and preferably much greater as described. The cooking operation is preferably carried on with a gas space at the top of the digester and this may conveniently be provided at this point in the process prior to the admission of the cooking steam and without release of the pressure below the desired minimum by admitting compressed air at a suitable pressure, say 125 pounds, from air line 13 to the top of the digester, valve 15 being opened to permit the discharge of a predetermined amount of acid from the digester back to the storage tank 7.

The chips being, as it were, water-logged by the acid forced into them under pressure, will sink, say to the level denoted by the line *a* in the digester, and the acid retained in the digester should be sufficient completely to cover these chips, say to the level indicated by the line *b*, whereupon valve 15 is closed and the air shut off. Experience has shown that the chips will continue to absorb acid slightly so that the pressure in the top of the digester will decrease but not substantially below the desired minimum pressure of 75 pounds which is utilized during the cook.

Without release of the elevated pressure within the digester the cooking steam is then admitted through steam line 17 under suitable control, herein indicated as an automatic control, effected by the instrument 19 of the recorder-controller type responsive to rate of flow and conveniently governing such rate of flow in accordance with a time variable and operating through the controlled valve 21 actuated by diaphragm motor 23. The pressure within the digester is maintained at a substantially constant value, say 75 pounds gage, by means of a discharge valve 25 in a discharge line leading to gas cooler 27 and thence back to the storage tank 7. I have herein shown this valve as operated by dia-

phragm motor 29 under automatic control of an instrument 31 of the recorder controller type and operating responsively to the pressure conditions in the digester regardless of 5 the amount of steam supplied.

It will thus be seen that the initial pressure placed upon the acid forcing the same into the chips is not released at any time but is maintained from the beginning and at a value 10 preferably at least as great as the desired cooking pressure and that this pressure is maintained with minimum variation throughout the entire period of cook.

It is important for reasons which will appear 15 that the differential in pressure between the incoming steam and the air space at the top of the digester be as small as possible. This can be accomplished by suitably increasing the size of the piping at the inlet to the 20 digester, as indicated in the figure, so as to obtain the required volume of steam at relatively low pressure and low velocity and therefore the required heat units for cooking. It will be understood that the rate of flow of 25 steam supplied necessarily varies at different stages of the cook and this may be governed manually or automatically by suitable design of the controlling instrument 19. Instruments which serve to control the operation of a dia- 30 phragm motor such as 23 in accordance with a curve whose coordinates are time and some other variable, as, for instance, rate of flow, are well known and do not need extended description herein.

In accordance with the process herein described, the pressure originally applied to the charge not only results in efficient penetration of the chips, thereby to abbreviate and improve the cooking process, but once 40 this pressure is applied it is maintained substantially constant throughout the duration of the cook. There is no great differential in pressure between the incoming steam line and the air space at the top of the digester. 45 The steam enters gently and instead of tending to "bore" its way through the charge along the center of the digester resulting in poor heating along the sides, the heat is distributed uniformly throughout the charge. 50 Relatively little disturbance of the liquid results due to the gentle admission of the steam and consequently, referring particularly to the sulphite process, relatively little sulphur dioxide gas is lost from the acid 55 to be discharged to the air space at the top from which it must be relieved weakening the acid and affecting the quality of the resultant pulp. As contrasted with the known processes in which the digester is at substantially atmospheric pressure when steam is admitted and in which the admission of steam to bring the digester to cooking temperature must, to avoid "boring" and violent agitation of the contents of the digester, be gradual 60 and effected over a period of hours with con-

stant watchfulness; the temperature may be easily and promptly raised to the desired point with resultant abbreviation of the time required for completing the cook. My process thus provides quickly cooking, better circulation of heat units throughout the liquid contents of the digester, conservation of the acid strength within the digester and more thorough cooking of the wood content by reason of the greater penetration of the chips due to the initially applied pressure. The cooking operation in accordance with the process described is so much simplified, adapting it to be efficiently carried out if desired, under 70 automatic control by instruments of known type.

I am aware that the invention may be embodied in other specific forms without departing from the spirit or essential attributes thereof, and I therefore desire the present embodiment to be considered in all respects as illustrative and not restrictive; reference being had to the appended claims rather than to the foregoing description to indicate the 80 scope of the invention.

I claim:

1. In the digestion of fibrous material the method which comprises completely filling the digester containing the fibrous charge with liquor under a pressure at least approximating the desired cooking pressure and introducing steam thereto to effect the cook while substantially maintaining such pressure.

2. In the digestion of fibrous material the method which comprises completely filling the digester containing the fibrous charge with liquor under a pressure at least approximating the desired cooking pressure, discharging a portion of the liquor without substantial fall of such pressure and introducing steam thereto to effect the cook while substantially maintaining such pressure.

3. In a digestion of fibrous material the method which comprises completely filling the digester containing the fibrous charge with liquor under a pressure at least approximating the desired cooking pressure, discharging a portion of the liquor by admission of gas under pressure to provide a gas space and introducing steam thereto to effect the cook while substantially maintaining such pressure.

4. In the digestion of fibrous material the method which comprises saturating the chips with liquor by an elevated pressure applied through a column thereof and thereupon introducing steam to effect the cook while maintaining a pressure substantially constant throughout the cooking period.

5. In the digestion of fibrous material the method which comprises saturating the chips with liquor by an elevated pressure applied through a column thereof, introducing steam to effect the cook while maintaining a pres-

sure of several atmospheres and regulating the cooking pressure by relieving the same to maintain a substantially constant value during the cook.

5 6. In the digestion of fibrous material the method which comprises saturating the chips with liquor at a pressure substantially exceeding the cooking pressure and exerted through a column of the liquor and intro-

ducing steam to effect the cook while maintaining the pressure at least substantially at the desired cooking pressure and maintaining such pressure substantially constant throughout the period of the cook.

70 In testimony whereof, I have signed my name to this specification.

HERVEY G. CRAM.
